(57) **CLAIM**

I claim the ornamental design for a carabiner keyring, as
shown and described.

DESCRIPTION

FIG. 1 is a front view of the carabiner keyring showing my
new design;

FIG. 2 is a rear view thereof; and,

FIG. 3 is a perspective view thereof.

The broken lines illustrating portions of the carabiner key-
ring form no part of the claimed design.

1 Claim, 3 Drawing Sheets

FIG. 1

FIG. 2

FIG. 3
